his Attorney.

UNITED STATES PATENT OFFICE.

ELMER L. VAN DRESAR, OF ST. PAUL, MINNESOTA.

TIE-PLATE RAIL-ANCHOR.

1,398,478.

Specification of Letters Patent. Patented Nov. 29, 1921.

Application filed July 27, 1921. Serial No. 487,879.

To all whom it may concern:

Be it known that I, ELMER L. VAN DRESAR, a citizen of the United States, residing at St. Paul, in the county of Ramsey and State of Minnesota, have invented certain new and useful Improvements in Tie-Plate Rail-Anchors, of which the following is a specification.

This invention relates to rail anchors for anchoring railway rails to the tie, to prevent the rails from creeping as on one way railway tracks, or generally, in the direction of greatest travel.

More particularly, the invention relates to that type of rail anchors designed to grip the base of the rail and be secured to the tie, an object of the invention being the provision of a simple, effective rail gripping device, cheap of manufacture, and capable of being secured to a tie, and consisting solely of duplicate unitary members having interfitting wedge surfaces, which coact when brought into frictional engagement to firmly grip the base of the rail. By the use of duplicate members, a single pattern is required, thereby simplifying the process of manufacture and effecting great economy in distribution for use, as well as avoiding a confusion among those entrusted with its application to the track.

The tendency of the track to move in a succession of waves under rolling loads is well known and is a condition which must be cared for in any device intended to control creeping of rails.

A further object of the invention, is the provision of a two member rail anchor the members thereof being provided with means for frictionally gripping the base of the rail, and arranged to extend transversely, side by side, between the base of the rail and the tie, and beyond opposite edges of the base, so that spike holes in said members may be placed immediately adjacent said edges, whereby the base of the rail and said members may be directly spiked, in superposed relation to the tie. An important advantage is gained by thus having the spikes in direct contact with the rail, causing the rail to loosen said spikes as much as may be necessary to accommodate wave movement of the track instead of throwing

this function on the anchor by spiking down the transverse section alone, which would throw all pulling stress on the anchor members, thus tending to loosen them and destroy their gripping efficiency. Obviously, the leverage will increase as the distance between the spike and the rail.

Another object of the invention is the provision of an anti-creeper, formed like a tie plate so as to function as such, the plate being split centrally into two parts, the split at right angles to the rail, each part carrying an integral jaw fitting over directly opposite parts of the inclined flat upper sides of the base of the rail, each jaw adapted to be hammer driven so as to slide up said inclined side until hammer tight, whereby the rail base is wedgely gripped at its inclined sides.

The accompanying drawings illustrate a rail anchor embodying the invention.

Figure 1 is a plan view of a fragment of rail and tie, showing the improved rail anchor in its applied position, one spike only being shown.

Fig. 2 is a side view of same.

Fig. 3 is a vertical sectional view on line 3—3 of Fig. 1, and

Fig. 4 is a perspective view of one of the component anchor members.

In the drawings A designates the tie, and B the rail. The rail is formed with the usual base, having a flat under surface and inwardly inclined upper sides 1, joined centrally, with generous sized fillets 2, to the web 3. The anchor comprises as stated, in the foregoing, two interlocking members which are exact counterparts of each other, each consisting of an elongated rectangular flat plate 4, having adjacent its long edge, spaced spike holes 5, arranged to receive the base of the rail between them, so that the lip 6 of the spike will extend over and engage the edge of the base.

Adjacent the ends of the plate and extending approximately to the longitudinal center thereof, is the undercut lug 7, the inner edge 8 thereof being parallel with the rail and extending to a point adjacent the base of the fillet 2. This inner edge is under cut to form an upper jaw member 9, which, in conjunction with that part of the top of the

plate forming the seat for the rail, constitutes a rail gripping V-shaped jaw. The gripping face 10 of the upper jaw member is flat and so inclined as to flatly engage the 5 inclined upper-surface 1 of the base. This face may be roughened, as by serrations, or teeth, to obtain a more powerful frictional engagement, in special cases, where an excessive rail wave movement exists. At the 10 juncture of the plate and upper jaw member, the latter is cut away at 11, the cut extending longitudinally the full width of the jaw, and laterally over a relatively small portion of the top of the rail base, said cut 15 constituting a clearance space or easement, to clear imperfections along the edge of the base and afford room for hammer driving the V-shaped jaw into position.

It will be noticed that the gripping power 20 of the jaw 9 is applied vertically to the base of the rail only and that no lateral or side contact with the rail is permitted at 11. An opening or clearance is intended to be maintained here at all times to permit of take up 25 in tightening the anchor and to guard against variations in rails of the same weight and sections.

As shown best in Fig. 1, the undercut lug 7 extends beyond the plate 4 and overlaps 30 the corresponding plate of the adjacent anchor member C, the extending portion of the lug constituting a wedge 12 directed outwardly longitudinally of the rail, and inclined slightly from the vertical toward the 35 rail. Above the plate, and extending outwardly beyond the wedge 12 to form an offset 13, the lug is formed with a driving face or anvil 14, whereby the initial anchor member may be driven into position without 40 danger of bruising the wedge. The lug is suitably ribbed to afford ample strength and conserve metal.

Located opposite the lug 7, and formed with an inclined bearing surface 15, adapted 45 to slidingly engage with the wedge 12 of the adjacent anchor member, is the driving lug 16, the bearing surfaces of the two lugs, when the anchor members are assembled, forming a dove tail slideway whereby to effect 50 a positive sliding engagement between the two assembled anchor members, along a line somewhat diagonal with respect to the longitudinal axis of the rail.

In the application of the anchor to the 55 rail, one of the units is placed under the rail, and driven into position by hammer blows directed to the driving face 14. The mating anchor member is now placed into sliding engagement with the previously positioned member, and both simultaneously driven toward each other by hammer blows on the driving lug 16, until the two members appear to no longer yield to hammer blows, or, in other words, are hammer tight. Ordinary railway spikes are now driven through

the spike holes into the tie, whereby the rail and anchor are firmly held positioned on the tie, the anchor functioning as an ordinary tie plate, thereby effecting a great saving of material, in railway construction. 70

It is to be noted, that my improved anti-creeper prevents creeping in either direction, thereby avoiding the necessity of a double equipment on single tracks or tracks used for traffic in both directions. By making the angularity of the wedges 12 as shown at a in Fig. 1, less in degree than the angle between the surface 1 of the base of the rail, and the rail seat the V-shaped jaws are driven with great force against the base. 80

Further, by constructing the anchor in the form of a tie plate, each anchor represents a saving of one ordinary tie plate, thus, further greatly reducing the cost of railway construction. 85

I claim:

1. A rail anchor for railway rails, comprising relatively movable members each adapted to grip one side of a rail base and having a part extending underneath the rail base to and beyond the other side thereof, the extending part of one member having positive slidable connection with the extending part of the other member beyond the rail, said sliding connection being disposed at an angle relative to the longitudinal axis of the rail, and openings in the anchor members adapted to receive, so that they will slide vertically therein, the shanks of spikes provided for holding the rail to the tie. 90

2. A rail anchor for railway rails, comprising two anchor members, arranged side by side, one member being a counterpart of the other, each member consisting of an elongated tie plate, having a central transverse portion constituting a rail seat, a wedge at one end of the plate extending laterally beyond the side thereof, a lug having a bearing surface at the opposite end of the plate, said wedge and bearing surface being 105 symmetrically arranged relative to said rail seat so that they will slidingly engage, respectively, the bearing surface and wedge of the adjacent counterpart member, said bearing surfaces being inclined to form a dove-tail slideway directed in a line which is diagonal relative to the longitudinal axis of said rail seat, rail gripping means on each anchor member adapted to grip the rail responsive to a sliding movement of the said 110 anchor members toward each other, and spike holes in each anchor member immediately adjacent the rail seat. 115

3. An anti-creeper for railway rails, comprising a tie plate divided into two parts 120 longitudinally of the tie, so that one part may be moved toward the other, the central portion of said plate extending transversely of the tie constituting a seat for the rail, interfitting projections on said plate parts con- 125

structed so as to positively and slidably connect the latter so that they will slide along a line which is diagonal with respect to said rail seat, a rail gripping jaw member on each plate part, the two jaw members being directed toward each other and adapted to frictionally engage the upper inclined sur-

face of the rail, responsive to a sliding movement of said plate parts, and spike holes in the plate parts located so that spikes passed 10 through said holes will grip the rail base.

In testimony whereof I affix my signature.

ELMER L. VAN DRESAR.
